ANGUS N. SMITH, OF FORTY FORT, PENNSYLVANIA, ASSIGNOR TO WALES ADDING MACHINE COMPANY, OF WILKES-BARRE, PENNSYLVANIA, A CORPORATION OF PENNSYLVANIA.

CALCULATING MACHINE.

1,415,125.

Specification of Letters Patent.

Patented May 9, 1922.

Application filed November 13, 1919. Serial No. 337,665.

To all whom it may concern:

Be it known that I, ANGUS N. SMITH, a citizen of the United States, residing in the borough of Forty Fort, Luzerne County, Pennsylvania, have invented new and useful Improvements in Calculating Machines, of which the following is a specification.

More particularly, this invention relates to means to interrupt the feed of paper in line spacing direction at one or more points along the platen.

As is well known, roller or cylindrical platens are provided with pressure rolls in frictional contact therewith; between which and the platen, the leading edge of a sheet or strip of paper is inserted, the feed or advance of the paper being effected by imparting a step by step rotation to the platen, or, where the construction warrants, to the pressure rolls.

In some cases, it has been customary to provide a single pressure roll substantially coextensive in length with the platen, but experience has proven it better to provide a series of groups or pairs of independently supported short pressure rolls along the platen, in place of the single long roll.

In the calculating, as well as the typewriter machine art, it has been found that where the pressure rolls at one point along the platen failed to properly grip the paper, either through improper adjustment, excessive wear, or because their peripheries became smooth and hard, the feeding action was correspondingly reduced, and if it happened that the feeding action of a sufficient number of the groups of pressure rolls at one end of the series became impaired, the sheet of paper was advanced a greater distance at one side than at the other, and the printed lines ran askew across the sheet, which was a source of great annoyance.

I have taken advantage of this idea and have elaborated the same to completely prevent the feed of paper at one or more predetermined points along the platen, while permitting the feeding action to proceed uninterrupted at other points.

In the key-set, crank-operated type of calculating machines, the items set up on the keyboard are printed in their entirety at one operation. Where so-called wide paper carriages are used, the carriage may be shifted

from column to column successively, relatively to the types, as in cross-tabulating, to enable a succession of items to be printed in a horizontal line across the sheet before the paper is advanced to bring another writing line to the printing point.

In some lines of accounting, as in adding sales tickets by departments, it is desired to list the individual sales on one strip of paper, print the total under each departmental list by a sub-totaling operation, shift the carriage to the next column after each sub-totaling operation, print the same total in such adjacent column, and clear the machine, after which the carriage is returned to the first column and the sales of another department listed therein.

Heretofore, such a system resulted in a considerable waste of paper, as the latter was fed at every operation of the machine, and blank spaces the length of the individual departmental lists intervened between the total amounts in that column appropriated to the listing of totals only, which wide spacing impeded the operator in picking up the totals when striking a grand total of sales, for instance.

In other classes of work, it is desired to list a number of items, some of which are to be printed in duplicate, and others of which it is not desired to duplicate. Thus, for example, in banks, it is customary to list the amounts of the individual checks cashed, those drawn on the home bank being contained in one list, of which an original only is desired, whereas the checks drawn on other banks are separately listed for clearing-house purposes, a copy being sent to the clearing-house and a copy retained by the bank.

Formerly, one method of performing this work, has been to feed two paper strips around the platen, the outside checks being listed and totaled on one strip and the home bank checks listed and totaled on the remaining strip, the carriage being shifted back and forth to bring one or the other paper strip opposite the types, as occasion required; a suitable transferring medium being arranged to print the list of outside checks in duplicate.

Obviously, the strips were fed simultaneously, and the entry of several successive

items on one paper strip resulted in leaving a long blank space between the items on the other strip, thereby unduly separating the items and also wasting paper.

- 5 My invention prevents the feed of the strip of paper which is not in use, while permitting the line spacing action of that strip which, for the time being, is opposite the types.
- 10 In still other classes of work, as in billing, my invention enables the operator to list the individual items and print the total on the sheets or bills, and also print the total on a separate strip. Under former methods, 15 the separate totaling strip would feed coincidently with the bills or sheets, and considerable distances would separate the totals printed on the totaling strip.
- 20 By the use of my invention, the separate totals are condensed so as to follow each other at the usual line space intervals for which the machine is set, and waste of paper thereby avoided.
- 25 To attain the foregoing and other objects, I provide means to cast off or disable certain only of the pressure rolls coacting with the strip or sheet of paper which is not in use, without interfering with the advance in line spacing direction of that sheet or strip which is positioned at the printing point.

And further, as in the case where two or more strips of roll paper are in use, I provide means to control the separate pressure rolls coacting with the respective paper strips, whereby as either paper strip is brought to the printing point, the pressure rolls coacting with the other paper strip or strips are cast off or displaced, to prevent the feed of such strips, the pressure rolls which coact with the particular strip of paper in use being released for effective operation.

To these and other ends, my invention includes certain novel features and combinations of parts, which will be more fully set forth hereinafter and particularly pointed out in the claims.

In the accompanying drawings, Fig. 1 is a rear view of a paper carriage equipped with one form of my invention;

Fig. 2 is a right hand end view thereof, showing the line space mechanism;

Fig. 3 is a vertical cross sectional view, through a paper carriage, parts being omitted, showing the selected form of paper feed disabling mechanism in idle position; and

Fig. 4 is a fragmentary detail view in cross section, showing the paper feed disabling means in effective position.

While my invention is not restricted in its application to the well-known Wales calculating machine, I have chosen to illustrate it in connection with such machine, examples of which are disclosed in U. S. patents to

Wales, 797,032, August 15, 1905; Kuntzler 1,206,863, December 5, 1916; Pentecost, 1,206,905, December 5, 1916, and 1,223,419, April 24, 1917, (the two latter showing the paper carriage mechanism), and Schuppe, 70 1,308,117, July 1, 1919, to which reference is directed for a more complete explanation of the general features and operation of the Wales machine.

A suitably supported carriage bracket 75 2067 (Figs. 2, 3 and 4) is provided with ways or guides 2067^m between which a carriage slide 2065 is shiftably mounted. End plates 2010 secured to the opposite ends of the carriage slide 2065, project upwardly, 80 and a platen axle 2004 journaled in the upper portions of the carriage end plates, carries a cylindrical platen 2094.

Stops 2018^b (Figs. 1, 2 and 3) shiftable along a tabulating bar 2092^b journaled at its ends in the opposite end plates 2010 of the carriage, releasably and singly engage an abutment 2091^a (Figs. 2 and 3) fixed on one of the carriage rails 2067^m, to hold the sliding carriage where adjusted. Pressure upon a finger piece 2022^a (Figs. 1 and 2) connected to one end of the tabulating bar 2092^b, rocks the latter against the tension of a restoring spring 481^a (Fig. 1) to release the effective stop from the abutment 2091^a, and permit endwise shifting of the carriage to position any desired column on a sheet of paper, or any strip of paper at the printing point.

Brace rods 2001^a and 2003 (Figs. 3 and 4) 100 connect the end plates, one of which rods 2003 may preferably lie beneath the platen 2094 and in the same vertical plane with the axle 2004 thereof.

Pairs of front compression roll supporting levers 2015^a are journaled intermediate their ends at intervals along the cross rod 2003 beneath the platen, the upper arms of the levers extending forwardly from the axis of the cross rod 2003.

A front compression roll 2097^m is journaled at its ends between the upper arms of each pair of front compression roll supporting levers 2015^a.

Similarly, pairs of rear compression roll supporting levers or bell cranks 2015^c are journaled at intervals along the cross rod 2003, with their upper arms extending rearwardly of the axis of the cross rod 2003, a rear compression roll 2097^m being journaled at its ends in the upper arms of each pair of bell crank levers 2015^c. The right and left hand members of each pair of rear roll supporting bell cranks 2015^c are located adjacent the respective right and left hand members of the corresponding pair of front roll supporting levers 2015^a, and together therewith, form independent groups, the front and rear rolls 2097^m and 2097^m of each group lying in tandem.

Sleeves 2044 on the cross rod 2003, interposed between the oppositely-extending pairs of front and rear supporting levers 2015^a and 2015^c, separate the levers and hold them in position against lateral displacement.

The lower arms of the respective oppositely-extending pairs of front and rear roll-supporting levers extend rearwardly and lie 10 substantially parallel with each other, the lower arm of the front roll-supporting lever 2015^a preferably lying above the lower arm of its adjacent rear roll-supporting lever, and a spring 2081 connects the arms of 15 each such pair of levers, to yieldingly press the rolls 2097, 2097^m against the lower convex face of the platen.

A paper table 2022^g extending between the end plates 2010 behind the platen 2094, projects downwardly and forwardly around beneath the platen, the paper table being slotted, as at 2022^m, to enable the pressure rolls 2097 and 2097^m to contact the platen.

The paper table or chute guides the leading edge of the paper to the bite between the rear pressure rolls 2097^m and the platen and thereafter to the bite between the front pressure rolls 2097 and the platen, after which the chute directs the leading edge of the 25 paper upwardly between the platen and the types 561, in the usual manner. Either sheets or strips of paper of varying widths may be fed about the platen. In case paper strips are used, the strip may be conveniently contained in a roll 1 mounted to rotate on a spindle 2007^a removably insertible through apertures in the parallel side frames 2027^e journaled on the brace rod 2001^a, and constituting the paper roll holder.

Generally, the paper roll holder overhangs the platen 2094, but the roll holder may be turned backwardly to the position shown in Figs. 2 and 3, to uncover the throat between the platen and the paper table 2022^g, when it is desired to feed a wide sheet of paper around the platen, in addition to a strip 2.

The compression feed rolls 2097 and 2097^m are cast off or released from the platen 50 against the tension of the springs 2081, by a universal release bar 2092^f, which is preferably oblong in cross section, and extends between the rearwardly-projecting arms of the front and rear roll-supporting levers 2015^a, 2015^c. The release bar 2092^f is journaled at its ends in the carriage end plates 2010 and is provided with upwardly-extending arms 2022 connected at their upper ends by a bail 2003^m positioned above the paper throat. Pressing the bail 2003^m rearwardly 55 turns the release bar 2092^f from its normal idle position, in which its major axis lies substantially parallel with the rear arms of the levers 2015^a, 2015^c, to a position at an angle to such rear arms, whereby to spread

apart the rearwardly projecting arms of the front and rear roll-supporting levers, and thereby rock the upper roll-carrying arms of the levers 2015^a, 2015^c away from the platen against the tensions of springs 2081, as fully 70 set forth in the patent to Pentecost, 1,206,905, above referred to.

Deflectors 2068^b may be conveniently mounted on the universal bail 2003^m, to deflect the paper strips, after having been 75 printed upon, away from the paper throat, the forward ends of the deflectors resting lightly on the platen to prevent the entry of the leading edge of the paper between the deflectors and the platen.

Step by step rotation of the platen, the compression rolls 2097, 2097^m being in contact with the platen, advances the paper in line spacing direction.

Such rotation is imparted to the platen 85 by the familiar reciprocating thrust bar 2026 of the Wales machine, the foot 2026^m (Figs. 2 and 3) of which bar normally contacts the universal line space bail 2002, and holds it at one limit of its travel.

Hangers 2016^d fast on stub shafts 2053^b, 2053, journaled in the respective right and left end plates 2010 of the carriage, suspend the line spacing bail 2002 in the path of the foot 2026^m, and a spring 2486 tends to rock 90 the bail forwardly towards the foot 2026^m.

A line spacing pawl 2014, whose free end is adapted to engage the teeth of a ratchet 2020 secured to the platen axle 2004, is pivoted at its lower end to a bell crank arm 2016 fastened to the stub shaft 2053^b, and a pin 2062 on the pawl normally contacts the arm to hold the pawl out of engagement with its ratchet 2020 against the tension of a spring 2082^d connected to the pawl.

During the operation of the machine, the reciprocating thrust bar 2026 is first withdrawn relatively to the universal bail 2002, which follows the retreating bar, under the influence of the spring 2486 and rocks the bell crank arm 2016 to retract the line spacing pawl 2014 and enable it to take a new bite on the ratchet 2020. The thrust bar 2026, on its return to its normal rearward position, forces the universal bail 2002 backwardly against the tension of its spring 2486, and through the bell crank arm 2016, causes the pawl 2014 to engage the ratchet 2020 and turn the latter and the platen a predetermined distance, until the bell crank arm again contacts the pin 2062 on the pawl and disengages the latter from its ratchet near the end of the return stroke of the thrust bar.

Due to the clamping action exerted by the compression feed rolls 2097 and 2097^m upon the paper inserted between the rolls and the platen, the latter as it rotates, feeds the paper in line spacing direction.

The foregoing mechanism is old and con-

stitutes a part of the present invention only in so far as it cooperates therewith to effect the new results now to be set forth.

It is obvious that the release of any one of the groups of front and rear compression feed rolls 2097, 2097^m, from contact with the platen, will deprive the paper of the feeding action of the rolls at that point, and I utilize this idea in effecting the objects of my invention.

In the embodiment herein illustrated, I have shown two paper roll holders (Fig. 1), arranged on the paper carriage in such relation to the groups of compression feed rolls 2097, 2097^m that one such group coacts with the platen to feed the paper strip 2 served from one of the rolls, and another group of compression feed rolls similarly coacts with the platen to feed the paper strip served from the remaining roll.

By shifting the paper carriage in any convenient manner first in one direction and then in the other, the paper strips are alternately brought to the printing point and presented to the types, to be printed upon.

Assuming that the operator is listing debits on one paper strip and credits on the other, for instance, the carriage must be shifted back and forth to bring the appropriate strips to the printing point opposite the types, in accordance with the respective entries. And under former constructions, that paper strip which is removed from the printing point, is fed simultaneously with the paper strip which is at the printing point.

Or, assuming that a sheet of paper and a paper strip have been led about the platen, the line spacing mechanism will feed both the sheet and strip simultaneously irrespective of the number of entries made on either.

My invention provides a simple, inexpensive means readily applicable to machines now in use, to prevent the feed and consequent waste of the separate papers by disabling the compression feed rolls 2097, 2097^m which formerly coacted with the platen to feed that piece of paper which is not being printed upon.

Referring more particularly to the independent feed of either of two paper strips, the rear arms of the front roll-supporting levers 2015^a, which carry the respective compression rolls 2097 coacting with the platen to feed the individual paper strips 2, may be hooked or provided with a reentrant bend, as shown in Figs. 3 and 4, to offset such arms from their companion rear arms of the rear roll-supporting levers 2015^c, and thereby enable the use of a spring 2081 of sufficient length and size to provide the requisite flexibility and strength to withstand the alternate separation of the respective groups of rear arms.

Beveled or cam faces 2015^m on the rear

arms of the front compression roll-supporting levers 2015^a oppose similar cam faces 2015^m on the rear arms of the rear roll-supporting levers 2015^c, the opposing cam faces diverging from their inner to their outer ends.

The introduction, under pressure, of a means between the opposed beveled faces of the respective front and rear roll-supporting levers 2015^a and 2015^c, will separate the levers to cast off the pressure rolls 2097, 2097^m, and as one convenient means to accomplish this result, I have provided an independently-operable releasing device for each of the respective groups of rolls coacting with the several paper strips 2, a description of one of which will suffice for both.

The upper end of a releasing lever 2015^s (Figs. 2-4) pivoted intermediate its ends, as at 2053^s, to a post 2053^e projecting laterally from and traveling with the carriage slide 2065, lies opposite the respective rear ends of the front and rear roll-supporting levers 2015^a, 2015^c, of one group of rolls, and is provided with ears 2015^p which carry a horizontal cross rod 2003^a, over which may be conveniently slipped a sleeve 2044^a. The rod and sleeve are of sufficient length to contact the beveled rear ends of the respective levers 2015^a and 2015^c supporting the opposite ends of its group of two rolls 2097, 2097^m. The lower end of the releasing lever 2015^s extends in proximity to the lowermost carriage rail 2067^m and carries a stud 355 on which may be journaled an antifriction roll 340^a adapted to ride onto and off at a cam rise 2067^r mounted on the carriage rail 2067^m.

After the carriage has been shifted to bring the paper strip 2 to the printing point opposite the types 561, the corresponding releasing lever 2015^s is in idle position (Fig. 3) with its spreading roll 2044^a lightly in contact with the divergent faces at the free ends of the rear arms of levers 2015^a, 2015^c, and the antifriction roll 340^a rests against the face of the carriage rail. In such position, the springs 2081 are free to press the feed rolls 2097, 2097^m against the platen 2994 or the paper strip 2 interposed between the platen and the rolls, so that the paper will be advanced at every line spacing operation, or as the platen turns.

When the carriage is shifted to displace one of the paper strips 2 from the printing point and bring another paper strip or a sheet to the printing point, the releasing lever 2015^s associated with the paper strip which is shifted from the printing point, travels therewith, and the antifriction roll 340^a rides up on one of the cams 2067^r, thereby tilting the upper end of the releasing lever 2015^s forwardly and forcing the cross rod 2003^a, or the sleeve 2044^a surrounding the rod, between the divergent faces 2015^m

at the free ends of the rear arms of the roll-supporting levers 2015^a, 2015^c, to spread them apart against the tension of their springs 2081. The upper arms of the roll-supporting levers 2015^a, 2015^c are thereby rocked away from the platen to cast off the pressure feed rolls 2097, 2097^m, and thus interrupt the paper feed at that point, so that rotation of the platen by the line spacing mechanism, or otherwise, is ineffective to feed the paper strip which has been displaced from the printing point opposite the type.

The releasing lever 2015^e, by its contact with the cam rise 2067^r, is maintained effective until the idle paper strip is again shifted with the carriage, back to the printing point, at which time, the antifriction roll 340^r rides off of the cam rise 2067^r.

To prevent damage, and injury to, or undue strain on, the spring 2081, when the releasing lever 2015^e is rocked to effective position by its engagement with the cam rise 2067^r, the ears 2015^p extend in advance of the spreading roll 2044^a and contact the rear edge of the universal pressure roll release bar 2092^r, as shown in Fig. 4, to arrest the spreading roll 2044^a before it can interfere with the springs 2081, and before it can slip past the high points of the beveled or inclined edges 2015^m.

It will be understood that as one paper strip 2 is brought to the printing point opposite the type, the remaining paper strip is displaced laterally therefrom, and that the pressure rolls 2097, 2097^m cooperating with the platen to feed the paper strip brought to the printing point, are rendered effective by the tension of the springs 2081, which latter force the rear arms of the roll-supporting levers 2015^a, 2015^c together to extrude the spreading roll 2044^a from between the beveled edges 2015^m; as the releasing lever 2015^e leaves the cam rise 2067^r.

It is obvious that when both a paper sheet and a strip are led around the platen, the groups of compression feed rolls 2097, 2097^m which coact with the platen 2094 to feed the sheet, may be disabled and restored to effective position, in the same manner, as is the group of feed rolls associated with the paper strip.

Changes may be made in the form and arrangement of the several parts set forth without departing from the spirit and scope of my invention.

What I claim as new, is:

1. The combination with a printing mechanism, including types; a single platen shiftable relatively thereto, to present any of a number of separate pieces of paper to the types; independent pressure feed rolls releasably pressed against the platen to coact with the several separate pieces of paper; and means to turn the platen to line space the

paper; of means to cast-off one or another of the pressure rolls as the platen is shifted axially to prevent the advance of one or another of the separate pieces of paper notwithstanding the rotation of the platen. 70

2. The combination with a printing mechanism, including types; a platen shiftable relatively thereto, to present any of a number of separate pieces of paper to the types; pressure feed rolls releasably pressed against the platen; and means to turn the platen to line space the paper; of means to automatically release one or another of the pressure rolls to prevent the advance of one or another of the separate pieces of paper notwithstanding the rotation of the platen. 75

3. The combination with a printing mechanism, including types; and a paper carriage bearing a platen, and shiftable relatively to the printing mechanism to present one or another strip of paper on the platen to the printing mechanism; separate pressure rolls to yieldingly press the respective strips of paper against the platen; and means to turn the platen to line space the paper strips simultaneously; of means, effective when the paper carriage is in one of its adjusted positions, at which one of the paper strips is presented to the types, to release the pressure rolls coacting with that strip of paper remote from the types, and thereby prevent the feed of that strip. 85

4. The combination with a paper carriage, including a single rotatable platen about which the paper is led; groups of pressure rolls; means to press the rolls yieldingly against the platen; and line spacing mechanism with which the platen and pressure rolls coact, to feed the paper step by step; of means to automatically release at least one group of pressure rolls relatively to the platen to render them ineffective to feed the paper, while permitting the other groups of pressure rolls to remain operative. 95

5. In a paper carriage, the combination with a platen; pressure rolls adapted to yieldingly contact the platen; and means to turn the platen to feed the paper, held between the platen and pressure rolls, in line spacing direction; of means to automatically cast-off the pressure rolls and thereby prevent the feed of the paper. 110

6. In a shiftable paper carriage, the combination with a platen; pressure rolls adapted to yieldingly contact the platen; and means to turn the platen to feed the paper, held between the platen and pressure rolls, in line spacing direction; of carriage-controlled means, effective when the carriage is in at least one of its positions, to automatically release the pressure rolls relatively to the platen and thereby prevent the feed of the paper. 125

7. The combination with a shiftable paper carriage, including a rotatable platen; and 130

- means to turn the platen to feed the paper in line spacing direction; of pressure rolls between which and the platen the paper is led; pivotally mounted levers to support the 5 rolls; means to yieldingly press the rolls against the platen; and means automatically insertible between the levers to release the pressure rolls relatively to the platen, whereby to prevent the automatic feed of the paper 10 in line spacing direction.
8. The combination with a shiftable paper carriage, including a platen, about which the paper is led; separate pressure rolls; means to press the rolls yieldingly against the platen, at least one roll adapted to press 15 a strip of paper against the platen; line space mechanism cooperating with the platen and rolls to feed the paper step by step; and types relatively to which the carriage is 20 shiftable; of means to automatically release that pressure roll active upon the paper strip, relatively to the platen, as the carriage shifts the paper strip to a point remote from the printing point of the types, to thereby 25 prevent the feed of the paper strip, while the other pressure rolls remain effective to feed paper in line spacing operations.
9. The combination with a suitable support; a paper carriage shiftable along the 30 support; a platen rotatably mounted in the carriage, and about which the paper is led; separate groups of pressure rolls; means to press the rolls yieldingly against the platen; and line spacing mechanism to coact with the platen and pressure rolls, to feed the paper step by step; of roll-releasing means 35 adapted to travel with the carriage and located adjacent one of said groups of rolls; and means with which the roll-releasing 40 means contacts when the carriage is in one of its adjusted positions, to operate the roll-releasing means to free the adjacent group of rolls relatively to the platen, and thereby prevent the feed of paper at that 45 point.
10. The combination with a suitable support; a paper carriage shiftable thereon; a platen rotatably mounted in the carriage and about which the paper is led; separate pressure 50 rolls; means to press the rolls yieldingly against the platen; and line space mechanism, with which the rolls and platen coact, to feed the paper step by step; of a lever pivotally mounted on the carriage to 55 travel therewith, one end of the lever adapted to lie adjacent one of the pressure rolls; and means effective upon the lever when the carriage, in its travel, arrives in a predetermined position, to rock the lever and cause 60 it to release its adjacent pressure roll relatively to the platen, and thereby prevent the feed of the paper at that point.
11. The combination with a suitable support; a paper carriage shiftable thereon; a 65 platen rotatably mounted in the carriage and about which the paper is led; separate pressure rolls; supports therefor means to press the rolls yieldingly against the platen; and line space mechanism, with which the rolls and platen coact, to feed the paper step by 70 step; of a lever pivotally mounted on the carriage to travel therewith, one end of the lever adapted to lie adjacent the supports of one of the pressure rolls; and a cam wiped by the opposite end of the lever when the 75 carriage, in its travel, arrives in a predetermined position, to rock the lever and cause the release of its adjacent pressure roll relatively to the platen, to prevent feed of the paper at that point.
12. The combination with a shiftable paper carriage; a platen rotatably mounted therein, and about which the paper is led; separate pressure rolls; means to press the rolls yieldingly against the platen; and line 80 spacing means coacting with the platen and pressure rolls, to feed the paper; of rocking levers to support the respective rolls, the free end of at least one of the levers having an incline formed thereon; a pivotally 85 mounted release lever; and means to swing the release lever to, and hold it in, contact with the inclined end of the roll-supporting lever, when the carriage is in a predetermined position, to shift the corresponding 90 pressure roll away from the platen, and thereby prevent the feed of paper at that point.
13. The combination with a shiftable paper carriage; a platen rotatably mounted 95 therein, and about which the paper is led; separate pressure rolls; means to press the rolls yieldingly against the platen; and line spacing means coacting with the platen and pressure rolls, to feed the paper; of rocking 100 levers to support the respective rolls, the free end of at least one of the levers having an incline formed thereon; and means to contact the inclined end of the roll-supporting lever to swing the latter and its roll 105 away from the platen, and thereby prevent the feed of paper at that point.
14. The combination with a shiftable paper carriage; a platen rotatably mounted therein and about which the paper is led; 110 groups of pressure rolls, each group comprising a front and a rear roll arranged in tandem; pairs of pivoted levers to individually support the respective front and rear rolls of each group at their opposite ends; means to press the rolls yieldingly against the platen; and line spacing means to coact with the pressure rolls and platen, to feed the paper; of means to prevent the feed of paper at a point on the platen, including a 115 releasing member, the free ends of the pairs of roll-supporting levers each having an incline, the inclines on the levers supporting the front and rear pressure rolls, respectively, diverging from each other, the re. 120

- leasing member adapted to enter between the divergent inclines; a release lever to support the releasing member; and means to actuate the release lever at a predetermined point in the travel of the carriage, to press the release member between the roll-supporting levers, and thereby rock the pressure rolls away from the platen, to prevent feed of the paper at that point.
- 10 15. The combination with a shiftable paper carriage; a platen rotatably mounted therein and about which the paper is led; groups of pressure rolls, each group comprising a front and a rear roll arranged in tandem; pairs of pivoted levers to individually support the respective front and rear rolls of each group at their opposite ends; means to press the rolls yieldingly against the platen; and line spacing means to coact with the pressure rolls and platen, to feed the paper; of means to prevent the feed of paper at a point on the platen, including a releasing member, the free ends of at least one pair of roll-supporting levers each having an incline, the inclines on the levers supporting the front and rear pressure rolls, respectively, diverging from each other, the releasing member adapted to enter between the divergent inclines; a release lever to support the releasing member; means to actuate the release lever at a predetermined point in the travel of the carriage, to press the release member between the roll-supporting levers, and thereby rock the pressure rolls away from the platen, to prevent feed of the paper at that point; and a stop on the release lever to limit its effective throw, and the extent of travel of the releasing member relatively to the inclined portions of the roll-supporting levers.
16. The combination with a suitable support; a paper carriage shiftable along the support; a platen rotatably mounted in the carriage, and about which the paper is led; separate groups of pressure rolls; means to press the rolls yieldingly against the platen; and line spacing mechanism to coact with the platen and pressure rolls, to feed the paper step by step; of roll-releasing means adapted to travel with the carriage and located adjacent one of said groups of rolls; and means with which the roll-releasing means contacts when the carriage is in one of its adjusted positions, to operate the roll-releasing means to free the adjacent group of rolls relatively to the platen, and thereby prevent the feed of paper at that point; said roll-releasing means adapted to be restored to idle position by the means which presses the feed rolls yieldingly against the platen, when the carriage is adjusted to another of its positions.
17. The combination with a shiftable paper carriage, including a platen about which separate pieces of paper are led, sepa-
- rate pressure rolls to press the respective pieces of paper against the platen; and line space mechanism operating upon the platen and pressure rolls, to feed the pieces of paper; of means to automatically cast off the pressure rolls active upon at least one of the pieces of paper, relatively to the platen, as the paper carriage shifts to one of its positions, while the pressure rolls active upon another of the pieces of paper remain effective; and means to automatically restore the cast-off means to idleness, when the carriage shifts from such position.
18. The combination with a printing mechanism, including types; a single platen shiftable relatively to the printing point of the types, to present any of a plurality of separate work sheets to the types; independent groups of pressure feed rolls releasably pressed against the platen to coact with the platen and feed the respective work sheets; and means to turn the platen to feed the work sheets; of means to automatically cast off that group of pressure feed rolls coacting with the idle work sheet to prevent the feed of such sheet notwithstanding the rotation of the platen.
19. The combination with a printing mechanism, including types; a single platen shiftable relatively to the printing point of the types, to present any of a plurality of separate work sheets to the types; independent groups of pressure feed rolls releasably pressed against the platen to coact with the platen and feed the respective work sheets; and means to turn the platen to feed the work sheets; of means to automatically cast off that group of pressure feed rolls coacting with the idle work sheet as the platen is shifted to bring one or another of the work sheets to the printing point, to prevent the feed of such sheet notwithstanding the rotation of the platen.
20. The combination with a printing mechanism including types; a single platen shiftable relatively to the printing point of the types, to present any of a plurality of separate work sheets to the types; independent groups of pressure feed rolls releasably pressed against the platen to coact with the platen and feed the respective work sheets; and means to turn the platen to feed the work sheets; of means to cast off the pressure rolls coacting with that work sheet which is idle and remote from the printing point, to prevent the feed of such sheet notwithstanding the rotation of the platen.
21. The combination with a printing mechanism, including types; a single platen shiftable relatively to the printing point of the types, to present any of a plurality of separate work sheets to the types; independent groups of pressure feed rolls releasably pressed against the platen to coact with the platen and feed the respective work sheets; and means to turn the platen to feed the work sheets; of means to automatically cast off that group of pressure feed rolls coacting with the idle work sheet to prevent the feed of such sheet notwithstanding the rotation of the platen.

- platen and feed the respective work sheets; and means to turn the platen to feed the work sheets; of means common to a plurality of groups of pressure rolls to automatically 5 cast off one or another of such groups which coact with the idle work sheet, to prevent the feed of such sheet notwithstanding the rotation of the platen.
22. The combination with a printing mechanism, including types; a platen shiftable relatively to the printing point of such types to present any of a plurality of separate work sheets to the printing point; independent groups of pressure feed rolls releasably pressed against the platen to coact therewith to feed the respective work sheets; means to turn the platen to feed the work sheets; and a universal means common to the several groups of pressure feed rolls to cast off such rolls; of means independent of the universal cast off means, to automatically release any group of pressure feed rolls which coacts with an idle work sheet remote from the printing point, to prevent the feed of such work sheet, notwithstanding the rotation of the platen.
23. The combination with a printing mechanism, including types; a platen shiftable relatively to the printing point of such types to present any of a plurality of separate work sheets to the printing point; independent groups of pressure feed rolls releasably pressed against the platen to coact therewith to feed the respective work sheets; means to turn the platen to feed the work sheets; and a universal means common to the several groups of pressure feed rolls to cast off such rolls; of means independent of the universal cast off means, to automatically release any group of pressure feed rolls which coacts with an idle work sheet remote from the printing point, as the platen is shifted relatively to the printing point, to prevent the feed of such work sheet, notwithstanding the rotation of the platen.
24. The combination with a printing mechanism, including types; a platen shiftable relatively to the printing point of such types to present any of a plurality of separate work sheets to the printing point; independent groups of pressure feed rolls releasably pressed against the platen to coact therewith to feed the respective work sheets; means to turn the platen to feed the work sheets; and a universal means common to the several groups of pressure feed rolls to cast off such rolls; of means independent of the universal cast off means, to automatically release any group of pressure feed rolls which coacts with an idle work sheet remote from the printing point, as the platen is shifted relatively to the printing point, to prevent the feed of such work sheet, notwithstanding the rotation of the platen.
25. The combination with a printing mechanism, including types; a platen shiftable relatively to the printing point of such types to present any of a plurality of separate work sheets to the printing point; independent groups of pressure feed rolls releasably pressed against the platen to coact therewith to feed the respective work sheets; means to turn the platen to feed the work sheets; and a universal means common to the several groups of pressure feed rolls to cast off such rolls; of means independent of the universal cast off means, to automatically release any group of pressure feed rolls which coacts with an idle work sheet remote from the printing point, as the platen is shifted relatively to the printing point, to prevent the feed of such work sheet, notwithstanding the rotation of the platen.
